DESIGN FOR A COMBINATION DISPLAYING AND STORING UNIT FOR BOTTLED GOODS OR THE LIKE

Louis Navone, Oakland, Calif.

Application January 29, 1941, Serial No. 98,497

Term of patent 7 years

To all whom it may concern:

Be it known that I, Louis Navone, a citizen of the United States and a resident of the city of Oakland, county of Alameda, State of California, have invented a new, original, and ornamental Design for a Combination Displaying and Storing Unit for Bottled Goods or the like, of which the following is a specification, reference being had to the accompanying drawing, forming part thereof.

Figure 1 is a perspective view partly broken away at both sides for the convenience of illustration, of a combination displaying and storing unit for bottled goods or the like, showing my new design; and

Figure 2 is a top plan view of the article, on a reduced scale, also being broken away at both sides.

I claim:

The ornamental design for a combination displaying and storing unit for bottled goods or the like, substantially as shown.

LOUIS NAVONE.
